(57) CLAIM

The ornamental design for a bottle as shown and described.

DESCRIPTION

FIG. 1 is an isometric view of the bottle showing our new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof, and,

FIG. 7 is a bottom view thereof.

The broken lines depict portions of the bottle that form no part of the claimed design.
